UNITED STATES PATENT OFFICE.

JAMES ELLWOOD JONES, OF SWITCHBACK, WEST VIRGINIA

COKE-PULLER.

SPECIFICATION forming part of Letters Patent No. 757,312, dated April 12, 1904.

Application filed July 21, 1903. Serial No. 166,462. (No model.)

To all whom it may concern:

Be it known that I, JAMES ELLWOOD JONES, a citizen of the United States of America, residing at Switchback, in the county of McDowell, in the State of West Virginia, have invented certain new and useful Improvements in Coke-Pullers, of which the following is a specification.

This invention relates to a coke-puller designed to be operated by machine for pulling coke from coke-ovens, and it is particularly adapted for discharging coke from beehive-ovens.

The invention is herein shown as applied to a coke-puller comprising an underworking scraper operative on its instroke to loosen coke for withdrawal and on its outstroke to withdraw the loosened coke.

The object of the invention is to insure the withdrawal of the full depth of coke on the outstroke.

Figure 1 of the accompanying drawings represents a longitudinal vertical section on line 1 1 of Fig. 2. Fig. 2 represents a plan, parts being broken out.

The same reference-numbers indicate corresponding parts in both figures.

This coke-puller is designed to be mounted on a machine adapted to thrust it into and retract it from the oven and swing it laterally in either direction to enable it to engage the coke at the sides of the oven. The machine shown in the expired United States Patent No. 446,936 may be used for this purpose.

The coke-puller comprises an actuating-bar 10, which is preferably rigid throughout, the rear portion thereof having a rack-bar or rack-teeth 11, corresponding to the rack-bar α of said patent, and the front portion 12 having a longitudinal slot 13. A cross-bar 14 is integral with or connected to the front end of the portion 12 and provided near its opposite ends at opposite sides of the scraper with slotted eyes 15 and 16.

A scraper 20 is disposed on the front portion 12 of the bar 10 and in the form shown is adapted to slide thereon. This scraper is hollow and of wedge-like form and comprises a bottom plate 21, of a breadth equal to the

desired width of the scraper, an inclined top plate 22, which extends upwardly and rearwardly from the front edge of the bottom plate, and a back plate 24, which connects the inner edges of the bottom and top plates and constitutes the thick side of the wedge-like body. The top plate is provided with a transverse slot 23, and a transverse pintle-rod 25 is disposed in a pintle-socket 26, attached to the plate 22 opposite the slot 23. The scraper is provided with a hollow shank 27, having a cross-bar or stud 28.

An adjustable coke-holder 30, preferably comprising a plate 31, having pintle-sockets 33 and 34 at its opposite sides, is hinged to the plate 22 by means of the pintle-rod 25 or otherwise. This plate in normal position lies over the outer face of the plate 22, below the slot 23, and is preferably provided with a rearwardly-projecting shank 32, which extends underneath the plate 22, above said slot. The front end of this plate is preferably beveled to coincide with the bottom of the bottom plate 21. The plate 31 is designed to lie flat against the upper face of the top plate 22 of the scraper on the inward stroke thereof and to swing into upright operative position for engaging the coke on the outstroke. Any suitable means may be employed for shifting the position of the plate. The means shown comprise slotted crank-arms 35 and 36, attached to the pintle-sockets 33 and 34 and extending inward substantially at right angles to the plate 31. Levers 40 and 50 are pivoted on studs, as 51, on the inner faces of the sides of the scraper. The lever 50 is provided at its upper end with a stud 52, which engages the slotted crank-arm 36, and the lever 40 is provided at its upper end with a stud 42, which engages the slotted crank-arm 35. The lower end of the lever 50 is provided with a stud 53, and the lower end of the lever 40 is provided with a corresponding stud. (Not shown.) These studs engage the slotted eyes 15 and 16, attached to the actuating-bar 10.

In the use of this coke-puller it is preferably mounted on a machine similar to that shown in said patent or any equivalent thereof. The coke-puller is thrust into the oven

and retracted therefrom by the machine, or this might be done by hand. The drawings show the coke-puller in position for an inward thrust. On the instroke the wedge-like 5 scraper moves over the bottom of the oven underneath the caked mass of coke a sufficient distance to make a proper drawing thereof and operates as a wedge to lift more or less of the coke under which it passes, usually breaking or separating said coke from said caked 10 mass. The motion of the actuating-bar 10 is reversed at the end of the inward stroke and said bar is drawn backward preparatory to the outward stroke. During the first part of 15 the backward movement of said bar the scraper 20 remains stationary under the weight of coke behind it until the front end of the slot 13 in said bar engages the stud 28 of the shank of the scraper. During this 20 backward movement of the bar 10 the coke-holder 30 is swung into vertical or approximately vertical operative position, as indicated by dotted lines in Fig. 1, whereby it is adapted to engage a large mass of coke. The 25 backward movement of the bar is continued and the outstroke of the scraper is effected while the coke-holder is in upright position. Consequently the coke behind said holder is drawn out through the door of the oven. The 30 first few strokes of the coke-puller are preferably in a direct line, two or more drawings being usually required to remove the coke throughout the diameter of a coke-oven. After this is done lateral thrusts of the coke-puller are made first to one side and then to 35 the other by means of the machine on which the coke-puller is mounted or otherwise.

The shank of the scraper may be in the form of an elongated bar extending back of the 40 machine or operator, and it may be provided with means for adjusting it into operative position independent of the resistance of the coke behind it.

I claim as my invention—

45 1. A coke-puller comprising an underworking wedge-like scraper movable over the bottom of a coke-oven, an adjustable coke-holder hinged to said scraper and provided with a crank-arm, a lever engaging said crank-arm, 50 and an actuating-rod connected with said lever for swinging said coke-holder into operative position.

55 2. A coke-puller comprising an underworking wedge-like hollow scraper movable over the bottom of a coke-oven and provided with a transverse slot in its upper face, an adjustable coke-holder hinged to said scraper at said slot and comprising a plate overlying the upper face of said scraper in front of said slot 60 and a shank underlying the upper face of said

scraper behind said slot, and means for swinging said coke-holder into operative position.

3. A coke-puller comprising an underworking wedge-like scraper, an actuating-bar having a sliding connection with said scraper for 65 moving it over the bottom of a coke-oven, an adjustable coke-holder connected with said scraper, and means connecting said actuating-bar with said coke-holder for swinging it into operative position.

70 4. A coke-puller comprising an actuating-bar, an underworking wedge-like scraper slideable on said bar and movable over the bottom of a coke-oven, an adjustable coke-holder hinged to said scraper, and provided with a 75 slotted crank-arm, and a lever connecting said slotted crank-arm with said actuating-bar.

5. A coke-puller comprising an actuating-bar provided with a cross-bar at its front end having eyes, an underworking wedge-like 80 scraper slideable on said bar and movable over the bottom of the coke-oven, and an adjustable coke-holder connected with said scraper, and provided with slotted crank-arms and levers connecting said crank-arms with said 85 eyes.

6. A coke-puller comprising an actuating-bar, an underworking wedge-like scraper slideable on said bar and movable over the bottom of a coke-oven, an adjustable coke-holder connected with said scraper and provided with a 90 slotted crank-arm, and a lever provided with a pin engaging said slotted crank-arm and having a slot-and-pin connection with said actuating-bar.

95 7. A coke-puller comprising an underworking wedge-like scraper, an actuating-bar for moving said scraper over the bottom of a coke-oven, said scraper having a sliding connection with said bar, an adjustable coke-holder connected with said scraper, and means for connecting said coke-holder with said actuating-bar.

100 8. A coke-puller comprising an underworking wedge-like scraper operative on its instroke to loosen coke for withdrawal and provided with a coke-holder adjustable after the instroke to engage and hold loosened coke on the outstroke, an actuating-bar for moving said scraper over the bottom of a coke-oven, 105 said bar and scraper having a limited sliding connection with each other, and means connecting said actuating-bar with said coke-holder for actuating the latter when one of said sliding parts moves relatively to the other 110 sliding part.
